UNITED STATES PATENT OFFICE.

ELBRIDGE BOYDEN AND WILLIAM H. BROWN, OF WORCESTER, MASS.

SPRING-HINGE.

SPECIFICATION forming part of Letters Patent No. 244,539, dated July 19, 1881.

Application filed May 26, 1881. (No model.)

To all whom it may concern:

Be it known that we, ELBRIDGE BOYDEN and WILLIAM H. BROWN, both of Worcester, in the county of Worcester and State of Massachusetts, have invented certain new and useful Improvements in Double-Acting Spring-Hinges for Doors; and we declare the following to be a description of our said invention, sufficiently full, clear, and exact to enable others skilled in the art to which it appertains to make and use the same, reference being had to the accompanying drawings, which form a part of this specification.

The objects of our invention are, first, to provide a spring-hinge mechanism arranged to operate on a single pivot or axial center and adapted for double action or for use upon doors opening both outward and inward, said hinge mechanism operating to close the door from either direction and for stopping and retaining it at central position, or as desired; second, to provide means for adjusting or regulating the throw or swing of the hinge, so that the door will stand at the required position when the hinge is at rest; third, to afford facilities for conveniently relieving or straining the tension of the spring, as desired, to give greater or less power and quickness of action; and, fourth, to furnish means for the adjustment of the pivot step-bearing for supporting the weight of the door and relieving the other parts of the hinge from strain and friction occasioned thereby. We attain these objects by mechanism constructed and organized for operation as hereinafter explained and illustrated, the particular subject-matter claimed being definitely specified.

In the drawings, Figure 1 represents an exterior side view of our improved spring-hinge as secured to the door-frame and door. Fig. 2 is a view of the internal mechanism, the case being divided at line $w w$, Fig. 1, and viewed in the direction indicated by the arrow. Fig. 3 is a vertical sectional view at line $w w$, Fig. 1, with the upper and lower parts separated from the central part of the hinge. Fig. 4 is a horizontal sectional view at line $x x$, Fig. 1, showing the pressure-bearing in the head of the hinge. Fig. 5 is a horizontal sectional view at line $y y$, Fig. 1, showing the pressure-bearing in the foot of the hinge. Fig. 6 is a plan

view of the top plate of the spring-cylinder. Fig. 7 is a plan view of the bottom plate of the spring-cylinder. Fig. 8 is a plan view of the ratchet-piece for adjustment of the spring. Fig. 9 is a plan view of the step-bearing devices for the pivot-rod.

Our improved double-acting spring-hinge is composed, primarily, of the head, the foot, and the central sections, said central section or part containing a coiled spring with its upper and lower ends (or suitable lugs connected therewith) projecting through curved slots in the top and bottom ends of said central section, and working in connection with curved recesses and lugs in the respective head and foot sections in such manner that when the door is swung or opened in one direction the spring will be compressed by action at its upper end, while its lower end or lug works free in the recess of the foot-section; and when the door is swung or opened in the opposite direction the spring will be compressed by action at its lower end, while its top end or lug works free in the recess of the head-section. The relative arrangement of the several slots, recesses, and lugs is such that the spring is at a position of equilibrium or at rest between the upper and lower actions when the door is closed or at a central position; hence the door swinging on a single axis and actuated by the single spring will be forced back to the position of equilibrium if opened either to the right or left and be retained at said position where the hinge mechanism is at rest. In connection with these primary operating parts may be combined devices for the adjustment, connection, and support of the mechanism, as will be explained.

A denotes the central cylinder or section containing the spring B, and fitted with suitable ear pieces or leaves, A', for attachment to the door.

C indicates the head-section, and D the foot-section, each of which has suitable ears, C' D', for attachment to the jamb-piece or frame. These latter may be joined together, if desired, but are preferably separate, as shown.

E indicates the pivot-rod, which forms the central axis on which the hinge turns. Said rod is arranged through the center of the cylinder A and spring B, with its ends extending into the head and foot sections, as shown.

F indicates an adjusting-sleeve for supporting and regulating the spring B. Said sleeve is, in the present instance, formed in three pieces, F' F² F³. The ends of the spring are hooked onto the parts F² and F³ as at f. The parts F' and F² are connected by ratchet-teeth b, so that the spring B can be strained up by turning the part F². This can be accomplished by the aid of a small pin or bar inserted in the holes e, (see dotted line, Fig. 2,) a recess or slot, c', being formed through the cylinder A to permit access thereto, as indicated. A hole, e², is provided for the insertion of a pin for locking the part F' in fixed position while effecting adjustment of the spring. G indicates a piece for forcing up the part F² and disengaging the ratchet-teeth for relieving the spring from strain, this operation being accomplished by inserting a small bar through the hole g and pressing up the pin G', first bringing the piece G over said pin G' by such movement of the hinge as is required. The parts F' and F³, which form the bearings or working ends of the spring, are provided with 25 studs or projecting lugs B² and B', that extend, respectively, through curved slots I and J in the bottom and top plates, I' J', of the central section or cylinder, A, and into corresponding slots or recesses, D² and C², formed in the bearing-pieces of the foot-section D and head-section C, where said studs B² and B' take bearing on the lugs or shoulders c d as the cylinder A is turned toward the right or left, and thereby effect the compression of the spring, 30 either with the lower stud, B', or with the upper stud, B², according to the direction of movement. The spring B presses the ratchet-teeth together and preserves the clutch of the parts, so that the action of the studs B' B² and the 35 operation of the spring B is substantially the same as though said studs B' B² were formed upon and by turning up the ends of the wire of which the spring is made, and in cases where adjustment of tension is not desired the spring 40 may be so constructed and the sleeve F be omitted.

The head and foot pressure-bearing pieces, C³ D³, which hold the ends of the pintle and engage the studs B² B' of the spring B, are 45 made adjustable by means of the arms C⁴ D⁴, which are fixed to and project back from said bearings into the space between the attaching-ears C' D', where said arms connect with adjusting-screws K K', which latter can be operated when the hinge is fixed to the jamb and door. The screws K K' pass through the attaching ear-plates C' D', one from the right and one from the left, their heads being at the exterior of said plates, while their points screw 55 into nuts confined to and bearing on said arms C⁴ D⁴ in opposition to the spring-studs B² B' in such manner that the operation of said screws K K' serves to turn the pressure-bearings with in their casings, causing variation of their position in relation to the studs B' B², and by carrying the lugs c d to the right or left regulate

the position of the door at rest. Small screws for retaining the bearings in proper connection with their cylindrical casings are arranged as at m.

N is the pintle-bearing, consisting of the disk N', screw-threaded to the foot-cylinder D, and connected by studs n n to the cap N², small springs being arranged beneath the heads of the studs n for pressing said disk and cap together. A step, S, of hardened steel, on which the end of the pivot-bar rests, is set into the center of the disk N'. The step is raised or lowered by turning the cap-plate N², which screws the disk up or down within the foot-cylinder without changing the position of the cap-plate N² relatively to the end of said cylinder.

The parts of the central section, A, can be all securely bound together by means of a collar, O, and nut P, arranged on the pivot-bar E, as indicated, so that when the step-bearing is raised the entire weight of the door will rest upon said step-S.

In securing the hinge to the door T and casing or jamb frame V the parts are beveled off in the manner indicated in Figs. 1, 4, and 5, to receive the flanges or screw-plates of the hinge, which may fit both sides of the wood-work, as illustrated, and a roll or bead, W, corresponding in size to the body of the hinge, is attached to the door or jamb between the hinges, thereby forming a "rule-joint" between the door and casing and making a neat and attractive finish.

The door may have but one spring-hinge, the others being made "dummy," or without the spring mechanism, if desired, as a single spring-hinge of our improved construction will operate the door as required, and prove sufficient under all ordinary circumstances.

In the operation the plates I' J' and the pressure-bearings C³ D³ act as stops for the spring B by engaging with the studs or projecting ends B' B². The spring is strained to the proper degree of tension and retained by the limit of the slots I J in the top and bottom plates, I' J', through which its studs B² B' pass. When the door is swung in the direction indicated by the arrows in Figs. 4 and 6 the stud B² is caught by the lug c and retained, the slot I permitting, while the stud B' is retained by the plate J' and carried around in the recess D², thus compressing the spring B by action at the top end, so that it will return the door until the stud B² reaches the end of the slot I and the stud B' reaches the lug d. These latter act as stops for the spring in its top-end action, and if the door is moved past the central position or as indicated by the arrows in Figs. 5 and 7, a similar action to that above described takes place in the opposite direction, and with the strain on the lower stud, B', which is thus forced back in the slot J by the lug d. Hence the spring devices have equal reactive power to return to the central position or to the position where the studs B²

B' have equal pressure on the plates I' J' and bearing-pieces C³ D³, which control the action of the spring B and establish a position of equilibrium between the upper and lower actions, so that the hinge can be worked in either direction with equal facility and efficiency.

If desired, our invention may be employed for a single-acting hinge by omitting the engaging-studs B' or B² at one end and securing 10 said end of the spring B in a fixed position in the case.

What we claim as of our invention, and desire to secure by Letters Patent, is—

1. The combination, with the central cylinder, A, and pivot-bar E, of the end plates, I' J', having slots I J, the spring device with studs B² B', and the end sections, C D, with adjustable bearing-pieces C³ D³, having recesses C² D², and stop-lugs c d, as and for the purposes 15 set forth.

2. The combination, with the spring B, of the adjustable supporting-sleeve F, carrying the studs B' B² at its upper and lower ends, and provided with ratchet-teeth b and holes e, 25 or their equivalent, substantially as and for the purpose set forth.

3. The combination, with the parts F' F² in the spring-adjusting sleeve F and the end plate, J', of the block G and pin G', substantially as and for the purpose set forth.

4. The combination, with the cylindrical sections C D, provided with flanges C' D' for attachment to the jamb or casing V of the bearing-pieces C³ D³, provided with arms C⁴ D⁴, and the adjusting-screws K K', substantially 35 as and for the purpose set forth.

5. The combination, with the central section, A, having the pivot-bar E rigidly secured therein, and the foot-section D, with bearing D³, of the adjustable supporting-step S, having its supporting-disk screw-threaded to the interior of said foot-section below said bearing, substantially as and for the purpose set forth.

6. The combination, with the foot section or cylinder D and pinle E, of the step-supporting disk N', screw-threaded to said foot-cylinder and carrying the step-bearing S, the cap-plate N², adapted to be revolved on the end of said cylinder, and the screws or studs n, with bearing-springs for uniting said disk and cap-plate with a yielding connection, substantially 45 as and for the purpose set forth.

Witness our hands this 20th day of May, A. D. 1881.
